(57) **CLAIM**

The ornamental design for an USB cable as shown and described.

DESCRIPTION

FIG. 1 is a perspective view of an USB cable showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of the USB cable where the USB cable is in a first configuration of use;

FIG. 9 is a perspective view of the USB cable where the USB cable is in a second configuration of use; and,

FIG. 10 is an enlarged view of portion 10 shown in FIG. 1. The dash-dash broken lines in the drawings depict portions of the USB cable that form no part of the claimed design. The dot-dash broken lines represent boundary of the enlarged portion and form no part of the claimed design. The drawings include a separation and a bracket which represent a symbolic break in length of the USB cable. The appearance of any portion of the USB cable between the break lines forms no part of the claimed design.
